UNITED STATES PATENT OFFICE.

CHARLES LEE FITCHET, OF CINCINNATI, OHIO.

COMBINATION SHADE AND DRAPERY FIXTURE.

1,244,305.

Specification of Letters Patent.

Patented Oct. 23, 1917.

Application filed November 2, 1914, Serial No. 869,810. Renewed March 27, 1917. Serial No. 157,858.

To all whom it may concern:

Be it known that I, CHARLES LEE FITCHET, a citizen of the United States, residing at Cincinnati, in the county of Hamilton and 5 State of Ohio, have invented a new and useful Combination Shade and Drapery Fixture, of which the following is a specification.

One of the objects of this invention is to provide a hinged shade and drapery holder, 10 which may be used on windows, doors and other places, and which will permit the shade and drapery to be swung to one side or the other of the window or door, thus facilitating the cleaning thereof, and also 15 making it possible to get the light from any angle.

Another object of the invention is to provide a shade and drapery holder of this type which may be positioned without using 20 a chair or step ladder, and which may be operated conveniently by a person while standing on the floor.

Another and no less important object of 25 the invention is to provide a combined shade and drapery fixture, which is pre-eminently practical and which may be cheaply manufactured and quickly assembled.

With these and other objects in view, the 30 invention consists of certain novel features of construction, combination, and arrangements of parts as will be hereinafter fully described, illustrated and claimed.

Referring to the drawings:

Figure 1 is an inside elevation of a window, showing my fixture in one of its embodiments applied thereto.

Fig. 2 is a section taken on the plane of line 2—2 of Fig. 1.

Fig. 3 is a vertical longitudinal sectional 40 view through the fixture, on line 3—3, Fig. 2.

Fig. 4 is an enlarged top plan view showing by solid lines the fixture in one position, and by dotted lines, the fixture in two other positions which it may assume, on line 4—4, 45 Fig. 1.

Fig. 5 is a side elevation of a slightly different form of the fixture from that shown in Fig. 1.

Fig. 6 is a view of another modification, 50 showing a fixture adapted to be secured to the inside edge of the casing.

Fig. 7 is an inside elevation of a drapery fixture with the drapery supporting rods in section.

Fig. 8 is an edge elevation of a stationary 55 bracket constructed so as to hold a fixture to a sash.

Referring in detail to the drawings by numerals, 1 designates as an entirety a window having a window casing 2 and a sash 60 3. In the preferred embodiment of my invention, I employ two stationary brackets which are rigidly secured to the window casing, and which are formed with vertical openings in their free terminals. Each 65 stationary bracket hingedly and detachably supports a swinging bracket and these brackets are designated 6 and 7. The brackets 6 and 7 are identical in construction with the exception that the parts are reversed so that 70 they will go together in pairs and because of this similarity, a description of one bracket will suffice to a clear understanding of the other.

The bracket 6 has a cylindrical barrel 75 8 entirely open at its lower end to receive an externally threaded nut 9 having a central opening 10 through which a hinged rod 11 extends. The rod projects upwardly through the barrel, through an opening 12 formed 80 in the top thereof, and is forced upwardly by a spring 13 bearing its upper end against a collar 14. A wing like extension 15 is cased integrally with the barrel and has an ear 16 on its free terminal having an opening 17 alined with the openings 10 and 12, and the hinged rod 11 is of such length as to project through the opening 17 while in its elevated position. The swinging bracket is attached to the stationary bracket by 90 placing the head of the stationary bracket between the upper end of the barrel and the ear 16, and then running the hinged rod through the head and ear.

The barrel is cast with a longitudinal external web or extension 18 of rectangular shape, and this projection 18 is formed on its inner side with a shade roller socket 19. An L-shaped arm 20 lying in a horizontal plane, and projecting away from the window casing is cast on the outside of the web or projection 18 as best shown in Fig. 4, and 100

its free end is recessed adjacent its inner edge to form a shoulder 21 for a purpose to be hereinafter set forth.

A second L-shaped arm 22 is detachably connected to the outside of the web or extension 18 preferably by means of screws 23 shown in dotted lines in Fig. 4, although it will, of course, be understood that any suitable fastening means may be employed.

10 Draperies, such as lace curtains, portières and the like, are strung on rods 24 and these rods are arranged in pairs as best shown in Fig. 4 and connected to end pieces 25 by screws or other suitable fasteners and said 15 end pieces are preferably connected to the arms 20 and 22 of the brackets 6 and 7 by screws 26 as shown. The shoulders 21 prevent the end pieces 25 from turning.

10 The shade roller 27, best shown in Fig. 2, 20 is supported by the sockets 19 and 28 and the shade 29 runs over a roller 30 supported between the webs 18. Guide pins 31 hold a shade properly in contact with the roller 30 and also prevent the shade being wrinkled.

25 After the curtains have been strung on the rods 24, said rods being arranged in pairs as before stated and spaced by the washers 24', the rods are connected to the bracket arms and then the fixture is raised into position for attachment to the stationary brackets 4 by means of the lift rods 32 which are threaded at their upper ends into engagement with enlargements 33. The hinge pins 11 have connected to their lower 30 ends flexible members 34 which may be either cords as here shown or chains. When the fixture is slipped over the heads of the stationary brackets the hinge pins are released and then spring into operative position 35 to hold the fixture firmly to the stationary brackets. Now if it is desired to swing the curtain to one side of the window one of the hinge pins is pulled downwardly to release one of the swinging brackets and 40 then the fixture may be turned about the other hinge pin. It will be understood that the lift rods may be made of any length desired and that instead of using flexible members 34 the hinge pins may be lengthened 45 so as to be easily grasped by a person standing on the floor.

50 In Fig. 5 I have shown a slightly modified form of stationary bracket 35 which makes it possible to attach the swinging brackets 36 to the inner side edges of the casing 2. The bracket 36 is substantially similar to the brackets 6 and 7 previously described and hence will not be described in detail. In this modification I have shown 55 only one pair of drapery supporting rods 37 but it will of course be understood that as many of these rods as desired may be used.

60 In Fig. 6 I have shown another modification of my fixture. In this figure the dra-

peries supporting rods are connected at their ends to end pieces 39 which fit between the head 40 and barrel 41 of the bracket and which are formed with openings for the hinge rod 42. The lift rods 43 in this form 70 of my invention are connected to the end pieces 39.

Fig. 7 shows still another form of my fixture and the only difference between this form and that shown in Fig. 6 is to be found 75 in the shape of the end piece 44. The form shown in Fig. 7 is especially adapted for use as a wall bracket to hold drapery thereagainst.

Fig. 8 shows a stationary bracket 45 80 which is used when the movable shade and drapery brackets are to be attached to a window sash such as indicated by the numeral 46.

85 From the foregoing description taken in connection with the accompanying drawings it will be apparent that I have provided a fixture which is capable of various modifications which is of simple construction and which may be conveniently positioned 90 and operated.

What I claim is:

1. The combination with a bracket having an opening extending therethrough, of a second bracket formed with a barrel and 95 an aperture ear in spaced relation to one end of the barrel, a spring pressed longitudinally movable hinge pin extending through the barrel and ear, the first mentioned bracket projecting between the barrel and 100 ear of the second mentioned bracket and the hinge pin passing through the opening thereof.

2. A combined shade and drapery support, comprising a pair of brackets adapted 105 to be rigidly secured to a support, a pair of brackets hingedly and detachably secured to the first mentioned brackets, means for individually disconnecting the second mentioned brackets from the first mentioned 110 brackets, and rods connecting the second mentioned brackets.

3. A combined shade and drapery holder, comprising a pair of brackets rigidly secured to a supporting member, a pair of 115 brackets removably and hingedly connected to the first mentioned brackets, means formed on the second mentioned brackets to support a shade roller, and rods connecting the second mentioned brackets, said rods 120 being adapted to support drapery.

4. A drapery fixture comprising a support, a horizontal drapery support, means to detachably and hingedly connect each end of the drapery support to the support, 125 and means to detach either end of the drapery support whereby it may be swung from one side to the other.

5. A drapery fixture comprising brackets, 130 a rod connecting said brackets, means to

detachably and hingedly secure the brackets to a support, and means to detach each bracket to allow the rod to be swung from either side to the other of the support to which it is attached.

6. The combination with a stationary bracket having an opening extending therethrough, of a rotatable and bodily movable bracket, a spring-pressed hinge pin carried by said bracket and projecting through the opening formed in the stationary bracket to connect said brackets to one another, and a flexible operating element connected with said pin.

15 7. In a drapery fixture, the combination with stationary brackets having apertures therethrough, of brackets, a rod connecting

said second brackets, spring-pressed hinge pins carried by said second brackets and projecting through the apertures in the first 20 brackets to detachably and hingedly connect the first and second brackets, flexible operating elements secured to and depending from the hinge pins, and lift rods secured to and depending from the second 25 brackets.

In testimony whereof, I have hereunto set my hand at Wheeling, W. Va., this 31st day of October, 1914.

CHARLES LEE FITCHET.

In presence of—

SARA R. GROVES,
EDMUND L. JONES.
